UNITED STATES PATENT OFFICE

DANIEL SNYDER GUSTIN, OF EAST ORANGE, NEW JERSEY, ASSIGNOR TO WESTINGHOUSE LAMP COMPANY, A CORPORATION OF PENNSYLVANIA

PREFOCUSED INCANDESCENT ELECTRIC LAMP

Application filed October 5, 1925. Serial No. 60,383.

This invention relates to the manufacture of electrical devices and particularly to a device having a light source disposed in a predetermined relative position with respect to other parts of the device.

In the manufacture of certain types of electrical devices, such for example as an incandescent electric lamp, when using such lamps in connection with apparatus wherein the light source must be positioned on a focal line, it is essential that the light source be positively and accurately positioned with respect to the means for securing the base to the apparatus.

Heretofore accuracy in the disposition of a filament for optical purposes has been obtained by the provision of expensive adjustable lamp supporting structure. On the other hand, lamps have been manufactured with a standard base and provided with auxiliary means for attaining a predetermined dimension between the light source and the base so that when a lamp was positioned in a socket the light source would be located in a predetermined position.

The necessity for the various expedients resorted to in properly locating a filament resulted from the fact that in the manufacture of an incandescent lamp under the usual standard practice, certain manufacturing inaccuracies occur which result in a slight variation in the position of a filament from the required focal position. It is, of course, possible that some filaments during the manufacturing of a lamp may be located properly but in order to insure a uniform product in the form of a lamp which may be employed for optical purposes, it is necessary that each lamp be so constructed that the filament will be positively positioned in a predetermined relation to the base portion of the bulb and within a very narrow tolerance.

An object of the present invention is, therefore, to provide a method of manufacturing an electrical device such as an incandescent lamp in such manner as to meet manufacturing conditions and to produce devices in which the light source is uniformly disposed.

Another object of the invention is to provide a lamp bulb with a base applied to a

bulb in the usual manner and adapted for a subsequent operation so that when applied to a socket the light source will be located in a predetermined position to said socket.

Another object of the invention is to provide a lamp with a co-operative socket to receive the base of the lamp and locate the filament thereof in a predetermined position.

Another object of the invention is to provide a lamp having a base applied to a bulb with the usual commercial accuracy and subsequently pierced to receive engageable members to hold the bulb with the filament thereof in a predetermined position.

Another object of the invention is to provide a lamp having a base adapted to be pierced to provide apertures in a given relation to a filament.

Another object of the invention is to provide a method of adjusting a lamp filament with respect to a supporting member by operations upon the base of the lamp to adapt the same for co-operations with a socket.

Other objects and advantages will be understood by reference to the following description.

In practicing the present invention I may provide an ordinary electric incandescent lamp with a blank or plain cylindrical form of base. The lamp may be constructed in the usual manner according to the common factory practice with only the usual commercial accuracy in locating the base in a given relative position with respect to a filament within a bulb. A lamp so produced may, according to my invention, be applied to a suitable fixture for supporting the lamp in relation to a lens system. The filament of the lamp may then be heated to produce a light source and the image reflected upon a suitable screen having divisions to indicate whether or not the filament is properly positioned. The lamp may then be adjusted until the reflected image shows that the filament is in a predetermined position. Means are provided for producing apertures in the base of the bulb to receive engageable members of a socket.

The lamp may be moved vertically or laterally until the image of the filament is properly located and punctures or apertures may

then be produced. The punching of the apertures in the base is so performed that notches having engageable edges are located a predetermined distance from the filament. A bulb so constructed is then ready to be placed in a suitable socket having members for engagement with the edges of the notches and the invention further contemplates the provision of a socket having suitable movable engaging members corresponding in number to the apertures in said base. When, therefore, a lamp base is inserted into the provided socket the movable members engage with the notches and hold the bulb with the light source a predetermined distance above the socket and consequently properly located with respect to the focal line of the system in which the lamp is employed.

It will be understood that sockets, as provided in accordance with the present invention, are to be properly positioned with respect to the reflector or element such as lens or mirror and that when a system is properly constructed lamps manufactured in accordance with the foregoing will be applicable for accurate disposition in such system. It will be evident that by reason of the present method and structure employed that a lamp may be manufactured in a rapid and economical manner under factory conditions, and that such lamps will be universal in uniformity so that when applied to a socket no discrepancy will occur with respect to the location of the light source relative to the focal line of the system or apparatus to which the lamp is applied.

The invention will be more fully understood by reference to the accompanying drawing in which:

Fig. 1 is a side view of a lamp and socket constructed in accordance with the present invention and shown partly in section.

Fig. 2 is a fragmentary perspective view of a base having notches with edges to engage with movable members of a socket.

Fig. 3 is a vertical sectional view of a socket having movable members to engage with the edges of notches of a base.

Fig. 4 shows a fixture for cutting slots at predetermined points in a base.

Fig. 5 shows another fixture whereby portions of the wall of a base may be bent inwardly adjacent to predetermined positioned slots.

Fig. 6 shows, diagrammatically, a lens system for projecting an image of a light source upon a screen.

Fig. 7 is a front view of a screen showing cross lines for locating an image.

Fig. 8 is a diagrammatic representation of an aligned filament and shows an exaggerated relation of a filament with respect to the means for locking the base in a socket.

Fig. 9 is a fragmentary view of a base and shows a modified form of notch.

Fig. 10 is a fragmentary view of a socket showing one of the movable members for engaging with the edge of the notch shown in Fig. 9.

Fig. 11 shows a section of a base having notches pressed therein without perforating the shell and

Fig. 12 shows a spring member of a base bent to provide a relatively large and contacting surface.

The invention may be practiced in connection with any electrical device employing a base or plug for application to a socket. The embodiment of the invention herein illustrated comprises a base 10 secured to a bulb 11 in the usual manner. The bulb may contain a light source or filament 12 mounted on support members 13 embedded in a press 14 of a stem 15 which is sealed to the bulb 11 in the usual manner. The light source 12 may be of any type or form depending upon the character of the bulb employed. Ordinarily, the distance between the base and the center of the filament varies slightly due to the failure of an operator to exercise the necessary care in properly positioning the filament when the lamp is made, that is, in properly disposing and securing the base to the bulb.

Ordinarily in the manufacture of incandescent electrical lamps insufficient accuracy is attained in positioning the filament for ordinary purposes. However, in the manufacture of lamps for use in connection with optical systems it is necessary that the light source of a lamp have a definite position with respect to the support thereof when disposed for operation. The usual commercial accuracy is not sufficient to produce a lamp with the light center of all lamps uniformly positioned. For the purpose of constructing a lamp to co-operate with a socket and to hold a filament in a predetermined position the base 10 may be blank when applied as by cementing to the bulb 11. As illustrated in Fig. 1 a socket 16 is provided to receive the base of the lamp, and may be provided with resilient, movable members 17, ends of which may project from a wall or shell 18 of the socket 16. The movable members may be provided in any suitable manner and, as shown, may consist of inwardly bent projecting tongues or spring members suitably secured to the shell 18. The shell may be fastened in a non-conductive casing 19 and held in place by a bolt 21 which bolt may be provided with a contact member 22. Disposed in a centrally located aperture 23 of the casing 19 is positioned a stem 24 having an enlarged end 25 to serve as a contact for engagement with lower central contact member 26 of the base 10. The stem 24 may be tensionally moved in contact with the member 26 under the action of a spring 27 and an end 28 of the stem 24 may project from the casing 19 and may be provided with a contact 29.

Fig. 10 is a fragmentary view of a socket showing one of the movable members for engaging with the edge of the notch shown in Fig. 9. Fig. 11 shows a section of a base having notches pressed therein without perforating the shell and Fig. 12 shows a spring member of a base bent to provide a relatively large and contacting surface. The invention may be practiced in connection with any electrical device employing a base or plug for application to a socket. The embodiment of the invention herein illustrated comprises a base 10 secured to a bulb 11 in the usual manner. The bulb may contain a light source or filament 12 mounted on support members 13 embedded in a press 14 of a stem 15 which is sealed to the bulb 11 in the usual manner. The light source 12 may be of any type or form depending upon the character of the bulb employed. Ordinarily, the distance between the base and the center of the filament varies slightly due to the failure of an operator to exercise the necessary care in properly positioning the filament when the lamp is made, that is, in properly disposing and securing the base to the bulb.

Ordinarily in the manufacture of incandescent electrical lamps insufficient accuracy is attained in positioning the filament for ordinary purposes. However, in the manufacture of lamps for use in connection with optical systems it is necessary that the light source of a lamp have a definite position with respect to the support thereof when disposed for operation. The usual commercial accuracy is not sufficient to produce a lamp with the light center of all lamps uniformly positioned. For the purpose of constructing a lamp to co-operate with a socket and to hold a filament in a predetermined position the base 10 may be blank when applied as by cementing to the bulb 11. As illustrated in Fig. 1 a socket 16 is provided to receive the base of the lamp, and may be provided with resilient, movable members 17, ends of which may project from a wall or shell 18 of the socket 16. The movable members may be provided in any suitable manner and, as shown, may consist of inwardly bent projecting tongues or spring members suitably secured to the shell 18. The shell may be fastened in a non-conductive casing 19 and held in place by a bolt 21 which bolt may be provided with a contact member 22. Disposed in a centrally located aperture 23 of the casing 19 is positioned a stem 24 having an enlarged end 25 to serve as a contact for engagement with lower central contact member 26 of the base 10. The stem 24 may be tensionally moved in contact with the member 26 under the action of a spring 27 and an end 28 of the stem 24 may project from the casing 19 and may be provided with a contact 29.

5 The socket 16 may be positioned in a lamp housing or other device which employs an electric incandescent bulb: the socket being permanently secured a predetermined distance from the focal line of a reflector or lens supported by the housing. According to the present invention a lamp is provided with means whereby the same may be secured in a socket and with the filament disposed in a predetermined position: For accomplishing the above a blank base 10 of a lamp is provided with notches or depressions 31 (see Fig. 2) into which the tongues or members 17 move when a base is introduced into the socket 16. The notches 31 are so formed as to provide relatively straight edges 32 for engagement with ends 33 of the members 17.

20 A base may be secured to a bulb with only the usual accuracy and provided with edges 32 located a predetermined distance from the center of the light source. The lamp thus constructed when disposed in a socket so that the edges 32 are held against the ends 33 of the member 17, will be properly disposed with the filament in a predetermined position. If, in addition to being out of position along the axial line of the bulb, the mount supporting the filament is slightly 25 out of alignment so as to cause a lateral displacement of the filament, the notches 31 may be so disposed as to compensate for such variation and bring the filament coincident with a given point on a predetermined focal 30 line.

35 The present invention, therefore, contemplates the formation of the notches 31 in a base at predetermined distances from the light source so that when the base is inserted for co-operation with a socket the proper disposition of the filament will be attained. A lamp manufactured in accordance with the present invention may be produced with the usual commercial accuracies in so 40 far as the assembly and union of the component parts of the lamp are concerned, the lamp or bulb having a base capable of being operated upon to be provided with notches or edges for the engagement with movable 45 members of a socket.

50 Any suitable means may be employed for piercing or punching the base to produce the notches and as shown in Fig. 6 a jig or fixture 34 may be provided in the form of a bracket having a centrally located opening 35, having rounded edges to permit a lateral adjustment of a bulb.

55 A spring actuated member 36 may be provided to engage the lower contact 26 of the base when the bulb is positioned in the fixture or bracket 34. The bracket may be metal and serve as a conductor by reason of its contact with the base 10 while the member 36 may serve as the opposite contact. Leads 37 and 38 may be provided for the passage of

60 electrical current from any suitable source of electrical energy (not shown), thus the filament of a lamp may be heated to incandescence to provide a light source. The bracket or fixture 34 may be part of a projection stem including a screen 39 and a lens 41. The lens may serve to project an image 40 of the filament upon the screen 39 and suitably positioned hair lines 42 and 43 are provided so that the lamp may be adjusted to give visible indication when the filament is centrally disposed with respect to the said lines upon a vertical adjustment of the lamp.

65 For the purpose of determining the lateral position of the filament with respect to a vertical axial line a mirror 44 is provided in co-operation with a lens 45 to throw an image of the upper portion of the filament upon the screen 39 so that by adjusting the lamp to locate the filament with respect to hair lines 46 and 47, a lateral adjustment of the filament with respect to a given point is attained. When so adjusted suitable rotating cutters 48 may be moved to form slots 70 in the wall of the base and thus produce the edges 32. Any suitable means may be employed for reciprocating the rotating cutters, the drawing merely showing the same in a more or less diagrammatic manner in order to convey a method of cutting the wall 75 of the base which will be obvious to those skilled in the art. Inasmuch as the cutters operate in a common fixed plane, it will be appreciated that no matter where the filament may be located with respect to the base, 80 by reason of the commercial inaccuracies, the slots may be cut a predetermined distance from the center of the filament in every bulb applied to the fixture or system.

85 It will be understood that in lamps produced under ordinary factory conditions the variation in the position of a filament with respect to a focal line governed by the relation of the base to the filament, or the position of the filament with respect to the axial line of the bulb does not vary to any considerable degree, that is the variation may be from a 32d to $\frac{3}{8}$ of an inch. This variation is too great for proper alignment of the filament on a predetermined line when the bulb 90 is positioned in a socket but is within a range that may be taken care of by variations in the positions of the aperture formed in the base by suitable means as the cutters 48. If desirable each cutter may be formed with a beveled 95 annulus 49 and forced toward the base so that the said annulus will engage the upper edge of the groove or incision formed and depress the wall to provide a cavity or curved surface 100

105 of the groove or incision formed and depress the wall to provide a cavity or curved surface 110 of the groove or incision formed and depress the wall to provide a cavity or curved surface 115 of the groove or incision formed and depress the wall to provide a cavity or curved surface 120 of the groove or incision formed and depress the wall to provide a cavity or curved surface 125 of the groove or incision formed and depress the wall to provide a cavity or curved surface 130 of the groove or incision formed and depress the wall to provide a cavity or curved surface

When a lamp base has been inserted into a socket and the members 17 have snapped into engagement with the edges 32 it will be apparent that the lamp will be locked against a direct vertical pull. After the lamp and base thereof is rotated, however, the members 17 will traverse the curved surfaces 51 and ride toward the cylindrical portion of the base, thus permitting a removal of the same when moved vertically upward.

As above set forth, although the slots and depressions in the base may be accomplished by the same tool or cutter 48, it may be desirable to cut the slots by means of cutters 50 as shown in Fig. 4 and subsequently depress portions adjacent to the slots thus provided by means of suitable formed tools 52 and shown in Fig. 5.

Although the members 17 may have round-ed ends 33 (as shown in Fig. 3) they may, if desirable, be pointed or angular like the end 53 shown in Fig. 10. When employing such angular or pointed members 17 in the socket, bases 10 may be provided with co-operating inverted V-shaped edges 54 (see Fig. 9). With this construction the lamp, when in the socket, is more rigidly held and centered against rotary movement.

As illustrated in Fig. 11 notches or recesses 55 may be formed in the base 10. The recesses may be so shaped as to provide an edge or straight surface 56 for engagement with the members 17 of a socket. The members 17 as shown in Fig. 12 may be made with their ends bent to provide contact surfaces 57 to afford a broader surface for engagement with the edges 32 of the notches 31 of the base 10.

From the foregoing it will be evident that a lamp manufactured with the filament slightly off-center may be provided with slots located by the above described optical means, which slots may lie in a plane indicated by the line 58 shown in Fig. 8.

A filament which was positioned slightly off-center in a lamp may be positioned by the above described adjusting means, at the intersection of a predetermined axial line 59 and the focal line 61. The distance between the plane 58 and the filament 12, and consequently the distance between the edges 32 of the base and the filament, will always be a predetermined distance, thus bringing the filament in the proper focal line as may be determined by the position of the socket in a lamp structure as used for signal, automobile, search lights or other service. The socket 16 may be sufficiently larger in diameter than the base of a lamp to allow for sidewise adjustment for engagement with the spring members 17. A bead 62 may be provided when desired at the upper edge of the socket to hold the base central with respect to the socket and allow for a slight sidewise adjustment.

In optical systems or lamp housings em-

ploying the present socket, it is to be understood that the socket is so positioned that when a bulb is inserted therein a filament will occupy the desired position with respect to the optical or projection system and obviously one lamp may be substituted for another without any adjustments to bring the filament in proper alignment.

Although a present embodiment of the invention and method is set forth and shown herein, it will be understood that other apparatus and modifications of the method may be resorted to without departing from the spirit of the invention as set forth in the appended claims.

What is claimed is:

1. An incandescent electric lamp comprising a bulb, a filament in said bulb, a base secured to said bulb, slots formed in said base in predetermined positions with respect to said filament and a concave portion formed from said base adjacent each of said slots.

2. The method of manufacturing an incandescent electric lamp which comprises providing a bulb having a filament therein and a base secured to the bulb in the usual manner, adjusting the lamp by optical means to determine a plurality of points on the base at predetermined distances from said filament and in perforating the base at said points.

3. The method of manufacturing an incandescent electric lamp which comprises providing a bulb having a filament therein and a base secured to the bulb in the usual manner, adjusting the lamp by vertical or lateral movement and determining by optical means when the filament is in a given position and in forming engageable members from the base disposed in predetermined positions with respect to the distance between the filament and said members and to the axial alignment of said filament.

4. The method of manufacturing an incandescent electric lamp which comprises providing a bulb having a filament therein and a base secured to the bulb in the usual manner adjusting the lamp by vertical or lateral movement or both and determining by optical means when the filament is in a predetermined position and in piercing the wall of said base to provide engageable edges in given positions with respect to the distance between the filament and said edges and to the axial alignment of said filament.

5. The method of so constructing a lamp having a luminous body in a bulb that said luminous body assumes a predetermined position when the lamp is placed in a socket having three inwardly projecting pins, which consists in securing a cylindrical base to said bulb, and indenting in the circumference of said base three recesses in predetermined angular relation to and at a predetermined distance from said luminous

body and located to cooperate with said pins of said socket.

6. The method of basing a lamp or similar device comprising a sealed glass bulb containing a luminous body, which consists in securing to said bulb with only usual commercial accuracy a tubular metallic base shell and then making in the wall of said shell engaging fasteners at predetermined 10 points in fixed and predetermined relation to said luminous body in the bulb.

7. The method of basing a lamp or similar device comprising a sealed glass bulb containing a luminous body which consists in 15 cementing one end of a metallic tubular base shell to said bulb in the usual way, and then forming pin engaging holes in the wall of said shell and at a fixed and predetermined distance from and in predetermined angular 20 relation to said luminous body in the bulb.

In testimony whereof, I have hereunto subscribed my name this 3rd day of October, 1925.

DANIEL SNYDER GUSTIN.
